United States Patent Office.

J. S. BURCH AND J. O. BURCH, OF BUFFALO, NEW YORK.

Letters Patent No. 94,393, dated August 31, 1869.

IMPROVED WINDOW-CURTAIN HOLDER.

The Schedule referred to in these Letters Patent and making part of the same.

To all whom it may concern:

Be it known that we, J. S. BURCH and J. O. BURCH, of the city of Buffalo, county of Erie, in the State of New York, have invented a new and improved Window-Curtain Holder; and we do hereby declare that the following is a full and exact description thereof, reference being had to the accompanying drawing, and to the letters of reference marked thereon.

The nature of our invention consists in applying two elastic rollers, a tape or cord being impinged between said rollers, so that the rollers, in combination with a tape or cord, and the roller of a window-curtain, may sustain the curtain in any position desired.

We refer to the drawing, which shows the arrangement more fully.

A represents the window-curtain roller.

The same is provided with a curtain in the usual way, also with a tape, B, which is secured with one end to said roller, as plainly seen in the drawing, while the other end runs down in between and through rollers C C.

Said rollers C C are covered with gum-elastic, or

other suitable material, for the purpose of impinging upon B.

The tape or cord is to be wound on in contrary direction to the curtain, so that if the tape or cord is pulled down, the curtain will be wound up, and that if the curtain is pulled down, the tape or cord will be wound up.

It will be observed that only one motion can be obtained by the working of the tape—the winding up of the curtain.

Claim.

Having thus described our invention,

What we desire to secure by Letters Patent, is—

The combination of the elastic rollers C C with tape or cord B and curtain-roller A, when constructed and operated as and for the use and purpose set forth.

J. S. BURCH.

J. O. BURCH.
